UNITED STATES PATENT OFFICE.

PLES H. SAMPSON, OF KANSAS CITY, MISSOURI, ASSIGNOR OF ONE-HALF
TO W. H. S. BRADY, OF KANSAS CITY, MISSOURI.

TENDER FOR TRACTION-ENGINES.

SPECIFICATION forming part of Letters Patent No. 750,065, dated January 19, 1904.

Application filed November 17, 1903. Serial No. 181,491. (No model.)

To all whom it may concern:

Be it known that I, PLES H. SAMPSON, a citizen of the United States, residing at Kansas City, in the county of Jackson and State of Missouri, have invented new and useful Improvements in Tenders for Farm-Engines, of which the following is a specification.

My invention relates to tenders for farm operative steam-engines, such as threshing-
engines, plowing or breaking engines, &c.

The object of my invention is to provide a means whereby the wheels under the tender may be made to track after the front wheels of the engine-carriage, thus providing means to admit of short turns being made with the engine and the tender.

Referring now to the accompanying drawings, Figure 1 is a side elevation of the tender and one of the front wheels of the engine-carriage, together with a tender-box in elevation secured to a platform in section. Fig. 2 is a plan view of the tender-carriage, together with a broken section of the front axle of the boiler and engine carriage, disclosing the means provided to make the wheels of the tender-carriage follow the tracks of the rear wheels of the engine and boiler carriage in making short turns. Fig. 3 is a plan view of the tender with the coal-receptacle removed. Fig. 4 is a vertical sectional view of the tender taken on line A A of Fig. 1, disclosing the means employed for causing the wheels of the tender to track after the hind wheels of the engine. Fig. 5 is an inverted plan view of the tender. Fig. 6 is an edge view of one of the two bars, with a right-angle extension and an elongated opening through said extension. These bars are adapted to secure the tender to the platform between the tender and the engine.

I will further proceed to describe my invention by referring to corresponding numerals on the drawings and specification, in which—

I designates the tender mounted on wheels. Said tender consists of a fuel-receptacle and a water-receptacle. The fuel-receptacle 2 is provided with longitudinally-extending ribs 3. Said ribs rest on the top edges of the wa-

ter-receptacle 4 in such a manner that the ribs and the fuel-receptacle form the top of the water-receptacle. The water and fuel receptacles are secured to the wheels by means of brackets 4. Said brackets 4 are secured to the sides of the water-receptacle in any suitable manner, the lower portions thereof forming a recess 5 between the bracket and a button 6, to which the bracket is secured. In order to firmly secure the bracket to the water-receptacle, I have provided stirrups 7. Said stirrups engage the recess 5, with their free ends extending upward passing through the longitudinally-extending ribs 3, and are made secure by means of nuts 8. Said stirrups are clearly seen at Fig. 5. The brackets 4 are provided with extended arms or ears 9. Through said ears are bolt-holes, as shown, and are adapted to rest upon vertical hubs 10. Said hubs are provided with vertical bores 11, correspondingly engaging with the bores in the ears. Passing through said bolt-holes and the bores in the hubs are bolts 12. Said vertical hubs are provided with extended spindles 13, passing through the hub in the wheels and secured therein by the usual spindle-nuts. Extending inwardly from said vertical hubs and integral thereto are arms 14. Pivots secured to the inner end of said arms are rack beams or links 15, their opposite ends being secured to a horizontal walking-beam 16. Said walking-beam is pivotally secured to a central brace or support 17, as shown, said central support extending forward and intersecting braces 17 18. The opposite ends of said brace from said intersections are secured to the vertical hubs by means of hub-bolts 11 passing through them, as indicated at Fig. 4. Extending from the vertical hubs rearward to the intersection of walking-beam 16 and the central support 17 are braces 19 and 20. These four braces form a rectangular configuration and are adapted to support the framework upon which the tender is supported. The framework consists of a cross-bar 21 and two longitudinal bars 22. At the rear ends of said longitudinal bars is a cross-bar 23. In connection with said cross-bar 23 is a yoke 24. Said yoke is rigidly se-

cured beneath the cross-bar 23 and also at the rear ends of the longitudinal bars 22. The object of said yoke will be described farther on.

Pivots secured to the inner extended arms 14 are a pair of forwardly-extending rods 25. The front ends of said extended rods are pivotally secured to the axle 26 of the front wheels of the engine-carriage by means of clips 27 and 28, which are secured to said axle. Secured to braces 17 and 18 are extensions 29 and 30. These extensions are provided with loops 31 and 32. Horizontally through said loop is a shaft 33. Secured to said shaft by means of elongated openings are extended brackets 34 and 35. Said brackets are clearly illustrated at Fig. 6. The object of these brackets is to secure the tender to the platform, (designated 36 in section at Fig. 1,) and the object of the elongated opening in said brackets is to admit of adjustment between the tender and the platform 36. Said brackets are rigidly secured to the platform by means of bolts, as shown.

The object of the yoke 24, already referred to, is to support the rear end of a draw-bar 37, the front end of which is jointed at 38. From 38 is an extension-rod 39, which loosely passes through a depending loop 40. The front end of said extension is made secure at any suitable point to the boiler or engine carriage. Passing vertically through said yoke 24 and cross-bar 23 are two pins or bolts 41 and 42. The object of these bolts is to confine the lateral movements of said draw-bar 35 more or less at this point, if necessary. The object of this draw-bar is to attach a separator or breaking-plows in the rear of the tender.

The operation of the principal features of my invention is as follows: Rods 25 being attached to the front axle of the boiler and engine carriage at their front ends and to the inwardly-extending arms 14 at their rear ends, it is clear that when the axle 26 is shifted in either direction from that as shown the inwardly-extending arms 14 will shift in the opposite direction, so that the shifting of the axle 26 will cause the wheels upon which the tender is mounted to track in the tracks of the hind wheels of the engine and boiler carriage, or approximately so.

Having now fully described my invention, what I claim as new, and desire to secure by Letters Patent of the United States, is—

1. In a tender for farm-engines of the character described, the combination of a pair of wheels, the tender mounted on the wheels, a pair of vertical hubs, outward-extending wheel-supporting spindles and inwardly-extending arms integral to said hubs, hub-supporting braces, a horizontal walking-beam

mounted on the rear of said braces, arms pivotally carried by the walking-beam and the inwardly-extending arms, and means communicating between said arms and the front axle of the engine-carriage, to cause adjusting movements of the rear wheels, substantially as described.

2. In a tender for farm-engines of the character described, a pair of wheels, a tender mounted on the wheels, a pair of vertical hubs, brackets secured to the tender and resting on said hubs, inwardly-extending arms integral thereto, outwardly-extending spindles, engaging the hub of the wheel, forwardly-extending reaches engaging the front axle of the engine-carriage, the rear ends thereof engaging the inwardly-extending arms of the vertical hubs, rearwardly-extending rack beams or links pivotally secured to the inwardly-extending vertical hub-arms, a horizontal walking-beam, the rear ends of the rack-bar engaging said beam, substantially as described.

3. In a tender for farm-engines of the character described, a pair of wheels, a tender mounted on the wheels, a pair of vertical hubs, inwardly-extending arms integral to said hubs, a pair of reaches, the rear ends pivotally connected to the inwardly-extending arms, the front end connected to the front axle of the engine-carriage, a pair of extending arms 29 and 30, a cross-beam, elongated loops integral thereto, a cross-beam engaging said loops, extended brackets 34 and 35 engaging said cross-beam and secured to the platform located between the boiler and the tender, substantially as described.

4. In a tender of the character described, a pair of wheels, the tender mounted on the wheels, a rectangular supporting-frame between the wheels, a pair of vertical hubs supported by said rectangular frame, inwardly-extending arms integral to said hubs, forwardly-extending reaches pivotally secured to said arms at their rear ends, rearwardly-extending rack-arms, the front ends secured to the inwardly-extending hub-arms, their rear ends pivotally secured to a vertical walking-beam, a stationary frame supported by the rectangular frame, a yoke carried by the rear end of said frame, a depending loop 40 secured to the platform, a longitudinal reach supported in said loop at one end and in said yoke at the opposite end, substantially as described.

In testimony whereof I affix my signature in the presence of two witnesses.

PLES H. SAMPSON.
